UNITED STATES PATENT OFFICE.

CLARENCE H. TAUBEL, OF RIVERSIDE, NEW JERSEY.

DESIGN FOR A STOCKING.

Application filed June 14, 1927. Serial No. 22,428. Term of patent 14 years.

To all whom it may concern:

Be it known that I, CLARENCE H. TAUBEL, a citizen of the United States, and a resident of Riverside, in the county of Burlington and State of New Jersey, have invented a new, original, and ornamental Design for a Stocking, of which the following description, in connection with the accompanying drawings, in a specification.

In the drawings:

Fig. 1 is a side elevation of a stocking embodying the design; and

Fig. 2 is an enlarged detail of the design illustrated in Fig. 1.

The design comprises vertical stripes of varying height at the high splice area, the longest thereof converging substantially to a point.

I claim:

The ornamental design for a stocking, as shown and described.

In testimony whereof, I have signed my name to this specification.

CLARENCE H. TAUBEL.
